(57) **CLAIM**

The ornamental design for a food container, as shown and described.

DESCRIPTION

FIG. 1 is a perspective view of a first representative embodiment of the food container showing our new design;

FIG. 2 is a right side elevation view of FIG. 1; the left side elevation view being identical thereto;

FIG. 3 is a front elevation view of FIG. 1; the rear elevation view being identical thereto;

FIG. 4 is a bottom plan view of FIG. 1;

FIG. 5 is a top plan view of FIG. 1;

FIG. 6 is a perspective view of a second representative embodiment of the food container showing my new design;

FIG. 7 is a right side elevation view of FIG. 6; the left side elevation view being identical thereto;

FIG. 8 is a front elevation view of FIG. 6; the rear elevation view being identical thereto;

FIG. 9 is a bottom plan view of FIG. 6; and,

FIG. 10 is a top plan view of FIG. 6.
